DESIGN FOR A BRACELET OR SIMILAR ARTICLE

Michael Chernow, New York, N. Y.

Application March 19, 1947, Serial No. 137,751

Term of patent 7 years

(Cl. D45—4)

To all whom it may concern:

Be it known that I, Michael Chernow, a citizen of the United States and residing at New York, in the county of New York and State of New York, have invented a new, original, and ornamental Design for a Bracelet or Similar Article, of which the following is a specification, reference being had to the accompanying drawing, forming part thereof, and in which:

Fig. 1 is an edge elevational view of a bracelet showing my new design, the dominant features thereof being illustrated in full lines;

Fig. 2 is a fragmentary plan view illustrating the elements disclosed in full lines in Fig. 1; and

Fig. 3 is an end view of the elements shown in full lines in Figs. 1 and 2; looking in the direction of the arrows 3—3 in Fig. 2.

I claim:

The ornamental design for a bracelet or similar article, substantially as shown and described.

MICHAEL CHERNOW.
